UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

TYPE-HOLDER.

1,137,386.

Specification of Letters Patent. Patented Apr. 27, 1915.

Application filed October 2, 1913. Serial No. 792,913.

To all whom it may concern:

Be it known that I, ALBERT B. DICK, a citizen of the United States, residing at Lake Forest, in the county of Lake and State 5 of Illinois, have invented certain new and useful Improvements in Type-Holders, of which the following is a specification.

This invention relates to type-holders for holding type in such a way as to facilitate 10 the operations of setting up and distributing a form of type.

The invention is of special application to type-holders of this character for use in connection with small printing equipments 15 adapted to be operated by persons of relatively little skill, such for instance, as printing equipments for office use.

The object of the invention is to effect certain improvements in the construction of 20 type-holders of this character which will make them more convenient to use and which will more thoroughly guard against displacement of the parts when the type-holder is being transported or when it is not in use.

25 A type-holder constructed in accordance with the invention consists preferably of a frame upon which a plurality of type-holding units are detachably mounted, each of these units consisting of a plurality of type-holding members having slots therein in which type are movable. In combination with a type-holder of this character, movable closing devices are employed for closing the ends of the type-receiving slots so as to 30 preclude the passage of type through the ends of these slots. Preferably two of these closing devices are employed, one at each end of the several units, and each closing device has a bar for each unit which bar is 35 adapted to extend along the ends of all of the slots of one unit.

The invention further involves the provision of a movable locking means for holding the several units in position upon the frame, 45 this locking means being movable so that whenever it is desired to do so any one of the units may be withdrawn from the frame for the purpose of inspection or repair or the substitution of a new unit.

50 By reason of the provision of the locking and holding means above mentioned, the type-holding units may be removably supported upon the frame of the holder, but when the holder is being transported or 55 when it is not in use, there is no danger

whatever of displacement of a unit. Also, when the type-holder is not in use, there is no danger of the type escaping from their respective slots because then the ends of the slots through which the type must pass to escape are closed; these ends of the slots may however be readily opened to permit the withdrawal of type when setting up a form and to permit the entrance of type when distributing.

60 The preferred embodiment of the invention is illustrated in the accompanying drawing in which—

Figure 1 is a front view of the type-holder broken away in part, Fig. 2 is a partial top 70 view of the holder, Fig. 3 is a central section of the holder and Figs. 4 and 5 are detail views hereinafter referred to.

Referring to these drawings, the type-holder consists of a frame formed from two 75 side-members 6 and 7 which are mounted upon a base 8 and connected by suitable cross rods 9. These side-frames 6 and 7 have pairs of parallel guides or ways secured thereto. In the present instance, three pairs 80 of parallel guides 10 are shown. Each of these guides has a groove or way 11 formed therein as shown in Figs. 1 and 3. Each pair of parallel guides is adapted to support a type-holding unit, this unit being slidable 85 into the ways 11 from the top thereof.

Each type-holding unit consists of end members 12 and 13 at the top and bottom and a plurality of strips 14 extending between these end members and forming between them type-receiving slots in which type 15 are movable. Each of these strips 90 14 has a groove 16 cut in each side thereof to form ways in which projections on the type 15 are received. The end members 12 and 13 and the strips 14 extending between them are all secured together and constitute a rigid type-holding unit which is removably mounted upon the frame of the holder. For this purpose, the pieces 12 are extended at 100 their ends slightly beyond the ends of the pieces 13 to provide projections adapted to enter within the ways 11 in the supports 10. At their extreme upper edges, the upper end pieces 12 are extended as shown at 17 to provide projections which will engage the upper ends of the supports or guides 10 to arrest the downward movement of the type-holding unit in the guides 10 when the unit has 105

reached the proper position.

The lower end piece 13 of each type-holding unit has a plurality of projections 18 thereon, each lying in line with one of the type-holding slots to check the downward movement of the type. But the sides of the type-holding slots are cut away immediately adjacent to the projections 18 so that the end type in each slot may be raised vertically out of the slot. This cutting away of the sides of the slots for a distance equal to the length of one type is shown at 19 in Fig. 1.

Movement of type out of the lower ends of the type-receiving slots when the type-holder is not in use is precluded by the provision of closing devices which may be moved into position for preventing such movement of the type or into position for permitting such movement when setting up a form of type. These closing devices consist of bars, each adapted to extend across a type-holding unit and all of them mounted upon the same support so that they move together. Two arms 20 are pivotally mounted upon the side frames 6 and 7 to turn about the same axis and a plurality of bars 21, one for each unit, extend between these arms 20 and are secured at their ends thereto. Preferably each bar 21 is of angular cross-section as shown in Fig. 3. When the arms 20 are in the position shown in Fig. 3, the bars 21 overlie the printing faces of the end type in the several rows. The arms 20 may be swung around on their pivot so as to carry the bars 21 away from the type to positions where they will not obstruct removal of the type.

Detachable locking means are provided for holding the arms 20 in the positions in which they are shown in Fig. 3. The preferred construction of this lock is that shown in Fig. 5. Each arm 20 has a strip 22 secured thereto bent to extend around the edge of the adjacent side-frame and carrying a small tubular member 23 in which a plunger 24 is movably mounted. This plunger 24 is pressed forward by a spring 25 and is provided with a button 26 whereby it may be withdrawn against the tension of its spring 25. The side-frames are provided with holes into which the ends of the plungers 24 are received and also with inclined notches 27 which serve to retract the plungers 24 when the arms 20 are moved to the closed position so that manual manipulation of the plungers 24 will not be necessary in order to lock the arms 20 in the closed position.

A similar closing means is provided for the upper ends of the type-receiving slots. Two arms 28 are pivotally mounted upon the side-frames and carry bars 29 of angular cross-section. When the arms 28 are in the positions shown in Figs. 3 and 4, the bars 29 lie close to the upper faces of the strips

14 so that if type were moved upwardly in the slots they would abut against the bars 29 and have their movement arrested thereby.

Means are provided for locking the three type-holding units against upward movement in the ways 11 and this locking means is independent of the closing devices for closing the upper ends of the type-receiving slots. Two arms 30 are pivotally mounted upon the side-frames 6 and 7 to turn about the same axis as the arms 28 and these two arms 30 are connected at their free ends by a cross rod 31. Each of the arms 30 has three studs 32 thereon projecting inwardly from the inner side of the arm and each of these studs is adapted to overlie the upper edge of one of the cross-members 12 of a type-holding unit when the arms 30 are in their Fig. 3 position. In Fig. 3, the studs 32 are shown in dotted lines coacting with shoulders upon the ends of the pieces 12. When in this position, the studs preclude upward movement of the type-holding units so that the units are held in the positions in which they are shown. Each of the arms 30 is provided with a locking device 33 of a construction similar in all respects to that shown in Fig. 5 except for the absence of the supporting piece 22. These locking devices 33 are adapted to coact with the side-frames 6 and 7 to hold the arms 30 in the locking positions in which they are shown. The arms 28 are pivotally mounted on the same axis as the arms 30 and they overlie the arms 30 so that when arms 30 are moved they carry arms 28 with them. But the arms 28 may be moved independently of the arms 30. These arms 28 connected by the rods 29 are provided with detachable locking devices 34 like the locking devices 33 and adapted to coact with the arms 30.

It will be seen that by detaching the locks 34, the bars 29 may be moved to inoperative position to permit distributing type. Also, the locking devices 33 may be operated and the arms 30 turned to inoperative position to permit one or more of the type-holding units to be removed as a whole. This movement of arms 30 may be effected either with or without first moving the arms 28. When the arms 20, 28 and 30, the bars 21 and 29 and the studs 32 carried by those arms are in the closed positions in which they are shown, movement of the type-holding units in their guides and movement of the type through either end of the type-receiving slots is precluded. These three retaining devices would be maintained in their closed positions when transporting the holder and when the holder is not in use to preclude disarrangement of the parts, but any one or all of these retaining means may be moved to its inoperative position at any time to permit of the desired movements of the type and the type units.

Having now described my invention, what I claim as new therein and desire to secure by Letters Patent is as follows:—

1. A type-holder comprising the combination of a frame, having pairs of guides thereon, a plurality of units, each removably mounted on one of said pairs of guides, each unit comprising a plurality of type-receiving members having type-slots therein, means for locking said units in said frame, and means movable as a unit into positions for preventing or permitting passage of type out of the ends of all of the slots, substantially as set forth.
2. A type-holder comprising the combination of a frame, a plurality of rows of type-receiving members thereon, each member having a slot in which the type are movable, means mounted on the frame and movable as a unit into positions for preventing or permitting passage of type out of the ends of all the slots, and a locking device for holding said means in its slot-closing position, substantially as set forth.
3. A type-holder comprising the combination of a frame, a plurality of rows of type-receiving members thereon, each member having a slot in which the type are movable, arms pivotally mounted on the frame, bars extending between said arms, the movement of said arms carrying each of said bars toward and away from the ends of the slots of one row of type-receiving members and into and out of position for precluding passage of type through the ends of all said slots, and a locking device for holding said arms in a predetermined position, substantially as set forth.
4. A type-holder having a frame, a plurality of type-receiving members thereon each having a slot in which type are movable, and two closing devices movably mounted on the frame, and adjacent respectively to the upper and lower ends of said members, each adapted to be moved into and out of position for closing one end of all of said slots to preclude passage of type through the ends of the slots and means for locking said devices in slot-closing position, substantially as set forth.
5. A type-holder comprising the combination of a frame, a plurality of rows of type receiving members thereon, each member having a slot down which the type are adapted to slide, said slots being closed at the extreme lower ends, and having their sides cut away adjacent to the said ends, so that the bottom type may be lifted out of each member at such openings, arms pivotally mounted on the frame and bars extending between said arms so positioned as to prevent passage of type through said openings when said arms are in one position, and to permit the same when said arms are in another position, substantially as set forth.
6. A type-holder comprising the combination of a frame, supports thereon having vertically-disposed guides, a plurality of type receiving members each having a slot down which type are slidible, secured together to form a single unit, supported in said guides, and removable therefrom only from the top, and a locking device movably mounted on the frame adjacent the upper end of said members when the latter are in position, and movable into and out of position for preventing the lifting of said unit from the guides, substantially as set forth.
7. A type-holder comprising the combination of a frame, supports thereon having vertically-disposed guides, a plurality of type-receiving members each having a slot down which type are slidible, supported in said guides and removable therefrom only from the top, and a locking device movably mounted on the frame, and movable into and out of position for preventing the removal of all of said members from the guides, and means for holding said device in position for preventing such removal, substantially as set forth.
8. A type-holder comprising the combination of a frame, supports thereon having vertically-disposed guides, a plurality of type-receiving members each having a slot down which type are slidible, supported in said guides and removable therefrom only from the top, a member pivoted to the frame, and movable into and out of position for preventing removal of said type-receiving members from the frame, and means for preventing removal of type from the upper ends of said slots, said means being mounted to be moved to inoperative position by the movement of said pivoted member out of operative position, substantially as set forth.
9. A type-holder comprising the combination of a frame, a plurality of rows of type-receiving members thereon, each member having a slot in which the type are movable, open at one end, said members being removably secured to said frame, means mounted on the frame and operable into and out of position for preventing removal of said type receiving members from the frame, means movable independently of said first named means into and out of position for preventing passage of type through the open ends of said slots, said slot-closing means being so mounted as to be moved to inoperative position by movement of said first-named means to inoperative position, substantially as set forth.
10. A type-holder comprising the combination of a frame, a plurality of rows of type-receiving members thereon, each member having a slot in which the type are movable, open at the top for the insertion of type therein and having openings adjacent their lower ends for the removal of type

therefrom, one at a time, said members being removably secured to said frame, and devices mounted on the frame and movable into and out of position for preventing the removal of said members from the frame, and for preventing the removal of type from the upper and lower ends of said slots, respectively, substantially as set forth.

11. A type-holder comprising the combination of a frame, supports thereon, a plurality of units each consisting of a plurality of type-receiving members having slots therein and each mounted removably upon the frame by coaction with said supports, pivoted arms mounted on the frame, locks for holding the arms in a predetermined position, and means on said arms for holding said units in position upon said supports, substantially as set forth.
12. A type-holder having a frame, sup-

ports thereon, a plurality of type-receiving members each having a slot in which type are movably secured together to form a single unit and detachably mounted on the frame by coaction with said supports, a detachable locking device mounted on the frame and movable into and out of position for holding said unit in its position on the frame, and a closing device mounted on the frame, movable independently of the locking device and adapted to preclude passage of type through the ends of said slots, substantially as set forth.

This specification signed and witnessed this 29th day of September, 1913.
